UNITED STATES PATENT OFFICE

2,443,920

TUBULAR HOT-AIR HEATER

Henry J. De N. McCollum, Chicago, Ill.; Thelma McCollum, executrix of said Henry J. De N. McCollum, deceased, assignor to Stewart-Warner Corporation, Chicago, Ill., a corporation of Virginia

Application March 4, 1943, Serial No. 477,908

4 Claims. (Cl. 126—116)

1

My invention relates to heaters, and more particularly to heaters of the internal combustion type.

Internal combustion heaters of the kind to which my invention pertains are commonly used in aircraft, and are commonly supplied with ventilating air by a ram into which atmospheric air is directed by the forward motion of the plane. In some aircraft installations, such heaters are supplied with ventilating air by blowers, and blowers, rams, or any other suitable air supply means may be utilized where my heaters are used for heating spaces other than the cabins or other enclosed parts of airplanes. In many instances, however, the pressure available to force the ventilating air through the heater is limited, and in aircraft installations particularly, it is desirable to reduce to a minimum the resistance of the heater to flow of ventilating air therethrough.

An object of my invention is to provide a heater which offers a minimum of resistance to flow of ventilating air therethrough.

Another object of my invention is to provide a heater wherein substantially all of the resistance to flow of ventilating air is frictional resistance between the air and the heating surfaces, so that a maximum amount of heating surface may be traversed by the ventilating air without increasing the resistance of the heater.

Another object of my invention is to provide a heater wherein the passages for the ventilating air are free from shoulders, pockets, and other means which would cause abrupt changes in direction of air flow, or which would facilitate the formation of eddy currents or low pressure areas, creating increased resistance to the flow of air through the heater.

Another object of my invention is to provide a heater of maximum efficiency, and having a minimum resistance to the flow of air therethrough.

Other objects and advantages will become apparent as the description proceeds.

In the drawings,

Fig. 1 is a longitudinal section through a heater embodying my invention. While this figure is mostly in longitudinal section, a small portion of the lower part of the muffler is shown in side elevation.

Fig. 2 is a transverse sectional view taken on the line 5—5 of Fig. 1; and

Fig. 3 is an end elevational view looking at the left-hand end of the heater shown in Fig. 1.

The heater shown in Figs. 1, 2, and 3 is con-

nected to a single air inlet 100 which supplies both the combustion air and ventilating air for the heater. The inlet 100 may be connected with a ram, blower, or other suitable source of air supply. This heater has an outer Venturi shaped casing 102 enclosing generally cylindrical, but longitudinally curved, walls 104, 106, and 108, and which are spaced from each other and from the casing 102 to form the combustion chamber and gas passage and to form passages for ventilating air and combustion air.

Part of the air supplied by the inlet 100 enters the combustion air passage 110 formed by the wall 108 and flows from the right-hand edge of this passage into a pipe 112 extending through the casing 102 and connected to the air inlet of a carburetor, indicated generally by reference character 114. This carburetor has the usual Venturi tube 116 provided with a fuel jet 118 supplied with fuel from a float bowl 120 connected by pipe 122 to any suitable source of fuel. A pipe 124 connects the upper part of the float bowl 120 with the interior of the pipe 112 so that the pressure difference between the pipe 112 and the throat of the venturi 116 is available to lift the fuel from the float bowl to the jet 118 and discharge this fuel into the Venturi tube to form a fuel and air mixture therein.

An induction tube 126 is connected to the outlet end of the Venturi tube 116 and extends through casing 102 and wall 104 into the right-hand or combustion chamber end of an annular space 128 between the curved walls 104 and 106. The induction tube 126 has a preheating portion 130 located in the combustion chamber and curved about the axis thereof, the outlet end 132 of this tube being arranged to discharge combustible mixture tangentially of the annular combustion chamber to form a ring of flame therein as described and claimed in my copending application Serial No. 477,080, filed February 25, 1943, now Patent No. 2,433,618, granted December 30, 1947. This preheating portion 130 of the induction tube may be made of any desired length to give the requisite preheating for the particular fuel with which the heater is designed to operate. The combustible mixture entering the combustion chamber is ignited by the electrical igniter 134 which may be of the same type and may be arranged as claimed in my copending application Serial No. 478,258, filed March 6, 1943, and issued as Patent No. 2,417,604 on March 18, 1947.

The hot gases formed in the combustion chamber flow lengthwise of the space 128 in a somewhat helical path and give up their heat to the

walls 104 and 106. The cooled gases are finally discharged to atmosphere through an outlet 138 and any suitable exhaust pipe connected therewith.

An annular and generally conical muffler 138 forms the right-hand wall of the combustion chamber and comprises a shell 140 containing sound absorbing material 142, such as stainless steel wool or glass wool. Openings 144 in the end wall 146 of this muffler acoustically connect the interior of the muffler directly with the combustion chamber, whereby sound created in this chamber may pass into the muffler and be absorbed. The annular and longitudinally curved walls 148 and 150 of this muffler shell constitute in effect continuations of the walls 104 and 106, respectively.

The annular space 128 which provides the combustion chamber and passage for the gases flowing therefrom, is surrounded by an annular ventilating air passage 152 formed between the casing 102 and walls 104 and 148. This passage in cross section is substantially Venturi-shaped, as clearly shown in Fig. 4, and has a short contracting inlet end 154 leading to a long throat-like portion 156 discharging into a flaring outlet portion 158 whereby this passage offers a minimum of resistance to the flow of air therethrough. Furthermore, the air flow is at a maximum adjacent the hotter portions of the wall 104 and absorbs a maximum of heat therefrom. In order to increase the transfer of heat from the wall 104 to the ventilating air, this wall has affixed thereto L-shaped strips 160 having radially projecting fins 162 which are scrubbed by the ventilating air as it passes through the throat-like portion 152 of this ventilating air passage.

A second annular ventilating air passage 164 is formed between the wall 106 of the combustion chamber and gas passage and the wall 108 of the combustion air passage. The ventilating air passage 164 is annular and has the same Venturi-like cross section of the ventilating air passage just described. L-shaped strips 166 are attached to the wall 106 of the gas passage 128 and have inwardly projecting fins 168 to facilitate the transfer of heat from the wall 106 to the ventilating air passing through the passage 164.

From the foregoing, it will be apparent that the ventilating air passages are shaped to offer minimum resistance to the flow of air therethrough. The combustion air passage 110 is not ideally shaped, from the standpoint of offering resistance to flow of combustion air therethrough. The volume of combustion air flowing through the passage 110, however, is relatively small compared to the cross sectional area of this passage, so that the shape of the passage 110 is relatively unimportant. I wish to point out, however, that even this passage is free from shoulders or other abrupt changes in the contour of its walls, and that the walls of this passage are smoothly curved and offer little resistance to flow of air therethrough. The walls of the gas passage 128 are also designed to offer little resistance to the flow of the gases of combustion from the combustion chamber to the outlet 138.

As clearly shown in Fig. 1, the left-hand ends of the walls 104 and 106 are welded or soldered together, and supporting brackets 170 are welded or soldered at spaced intervals to the left-hand end of the wall 104. These brackets 170 are bolted to U-shaped straps 172 and 174 which serve to support the walls 104, 106, and 108 in the casing 102 to which the U-shaped straps 172 are

bolted or otherwise secured. The right-hand ends of the walls 104 and 106 are attached to the left-hand end of the muffler 138 and spacing bars 176 and 178 and brackets 180, 182, 184, and 186 position and secure the right-hand ends of the tube 108 and muffler 138 in the right-hand end of the casing 102.

It will thus be seen that I have provided a lightweight, highly efficient heater offering a minimum resistance to the flow of air therethrough, so that a relatively low source of air pressure is capable of causing the ventilating air to traverse a maximum heating surface. These advantages are obtained in a heater which can be easily manufactured of conventional materials and which is sufficiently sturdy to give long and trouble-free service. Because of its light weight, high heat output, and low resistance to air flow, this type of heater is particularly adapted for aircraft use, but is not limited to such use and is capable of general application.

While I have illustrated and described a preferred embodiment of my invention, it is to be understood that my invention is not limited to the particular details shown and described, but may assume numerous other forms, and that the scope of my invention is defined in the following claims.

I claim:

1. A heater of the class described comprising a plurality of tubular walls spaced from each other and arranged coaxially, the outermost two of said walls forming a ventilating air passage therebetween, the innermost pair of walls forming a second ventilating air passage therebetween, said walls forming a gas passage and combustion chamber between said air passages, means forming an inlet for said ventilating air passages, means for supplying a combustible mixture to said gas passage at the end thereof opposite said air inlet, a carburetor for supplying said combustible mixture, and a combustion air passage for said carburetor formed by said innermost annular wall and receiving air from said air inlet.

2. A heater of the class described comprising means forming an annular combustion chamber, an annular muffler forming an end wall of said combustion chamber, means providing a gas passage communicating with said combustion chamber, means providing a ventilating air passage surrounding said gas passage, combustion chamber, and muffler, and means providing an air passage inwardly of said gas passage, combustion chamber, and muffler, said air passages being of Venturi-like longitudinal section.

3. A heater of the class described comprising a plurality of tubular walls spaced from each other and arranged coaxially, the outermost two of said walls forming a ventilating air passage therebetween, the innermost pair of walls forming a second ventilating air passage therebetween, said walls forming a gas passage and combustion chamber between said air passages, said air passages being of Venturi-like longitudinal section, means forming an air inlet for said ventilating air passages, and means for supplying a combustible mixture to said gas passage at the end thereof opposite said air inlet including a carburetor and a combustion air passage for said carburetor formed by the innermost annular wall and receiving air from said air inlet.

4. A heater of the class described comprising a plurality of tubular walls spaced from each other and arranged coaxially, the outermost two of said walls forming a ventilating air passage therebetween, the innermost pair of walls forming a

second ventilating air passage therebetween, said walls forming a gas passage and combustion chamber between said air passages, said air passages being of Venturi-like longitudinal section, means forming an air inlet for said ventilating air passages, and means for supplying a combustible mixture to said gas passage including a carburetor and a combustion air passage for said carburetor formed by the innermost annular wall and receiving air from said air inlet.
